CARPET SWEEPER AND CONTROL

Berthold R. Thiele, Ripon, Wis., assignor to Speed Queen Corporation, Ripon, Wis., a corporation of Delaware

Original application November 17, 1944, Serial No. 563,845, now Patent No. 2,602,175, dated July 8, 1952. Divided and this application June 6, 1951, Serial No. 230,130

4 Claims.

(Cl. 15—41)

1

The present invention relates to carpet sweepers of the type having two dust pans disposed within a translatable casing for catching dust particles swept from a floor covering by a rotatable sweeper brush disposed between the pans.

One object of the invention is to provide a carpet sweeper of the above type with a simplified dust pan control which is selectively operable to maintain the pans in either open or closed position and which is at the same time conveniently accessible to the user for dumping the sweepers.

Another object is to provide a sweeper with a dust pan control of the character recited which is arranged for cooperation with the bail of the sweeper handle to effect certain improvements in the operation of the sweeper and to maintain the sweeper handle in raised position when the sweeper is not in use.

Other objects and advantages will become apparent as the description proceeds. In the accompanying drawings:

Figure 1 is a small scale plan view of a sweeper embodying the features of the present invention.

Fig. 2 is a small scale end view of the sweeper showing the sweeper handle in raised position.

Fig. 3 is a fragmentary sectional view on a larger scale taken along line 3—3 of Fig. 2, with certain parts eliminated for clarity in illustration.

Fig. 4 is a fragmentary perspective view showing the relationship of an element of the dust pan control to one dust pan.

Fig. 5 is a fragmentary sectional view taken generally along line 5—5 of Fig. 3.

Fig. 6 is a vertical sectional view on an enlarged scale taken along line 6—6 of Fig. 1 with certain sweeper parts left out for clarity in illustration.

Fig. 7 is a fragmentary sectional view taken along line 6—6 in Fig. 1, and showing the dust pan control and one of the pans in dumping position.

The present application is a division of my copending application Serial No. 563,845, filed November 17, 1944, (now Patent No. 2,602,175, issued July 8, 1952).

Referring more particularly to the drawings, the sweeper forming the instant embodiment of the invention comprises a casing 11 adapted to be moved back and forth over a carpet or the like by means of a handle 12 connected to the casing by a bail 13, Figs. 1 and 2. Support for the casing is provided by floor wheels 15. A rotatable brush 16, Fig. 2, is longitudinally disposed within the casing 11 in position for sweeping dust particles from a carpet or floor covering into two dust pans 17, 18 mounted in the casing on opposite sides of the brush, Figs. 3, 5, and 6. It

2

will be understood that the sweeper is of generally symmetrical construction and that structural elements on one side or end of the sweeper find their counterparts on the opposite side or end of the sweeper.

The casing 11 is designed to provide a relatively large inner compartment 20, Figs. 3, 5, and 6, for the accommodation of the dust pans 17, 18 and the sweeper brush 16, shown only in Fig. 2. Two smaller compartments 22 are also provided at opposite ends of the casing, Figs. 3 and 5, for the accommodation of the floor wheels 15 and related parts (not shown) for mounting the wheels and driving the sweeper brush.

As to the general construction of the casing 11, the inner compartment 20 is defined by two spaced end plates 24 vertically positioned in the casing and suitably attached to opposite ends of an arched cover plate 25, Figs. 3, 5, and 6. Corresponding side edges of the end plates 24 are interconnected by side rails 26, the ends of which extend somewhat beyond the end plates. The end compartments 22 are defined by the respective end plates 24 and by two end shells 28, Figs. 3 and 5 suitably attached to the opposite ends of the cover plate 25 and the side rails 26.

In the present instance, the end plates 24 are each formed with a vertical slot 29 extending upwardly from the lower edge of the plate, Fig. 6. As fully described in my copending application previously identified, the slots 29 thus provided in the respective end plates are adapted to receive in assembled relationship therewith the opposite ends of a sweeper brush assembly (appearing only in Fig. 2).

The dust pans 17 and 18 are disposed in the casing compartment 20 on opposite sides of the end plate slots 29, Fig. 6. As to the structural details of the pans, it will be seen that each includes an elongated floor plate 30 bounded by marginal edge side flanges 32 and opposed end flanges 33 designed to retain dust in the pans. The outer side flange 32 of each pan is arranged to engage the contiguous side rail 26 and to form a dust-tight seal therewith upon closure of the pan. The inner side flange 32 of each pan extends upwardly and outwardly a substantial distance, Fig. 6, for cooperation with the sweeper brush, shown only in Fig. 2, in bringing about maximum sweeping efficiency. The opposite end flanges 33 of each pan extend upwardly from the pan floor plate 30, and interconnect with corresponding ends of the side flanges 32, each end flange decreasing progressively in height from the inner to the outer side flange.

Each of the pans 17 and 18 is pivotally supported in casing 11 for swinging movement between a closed or dust catching position, Fig. 6,

and an open or dumping position, Fig. 7. As shown in Figs. 3 to 7, each inner corner of the respective pans is provided with an inwardly extending supporting flange or lug 34 which is, in effect, an extension of the contiguous end flange 33. The respective supporting flanges 34 are suitably apertured to receive cooperating pivot pins 36 projecting from the inner faces of the end plates 24, one pin being provided for each flange.

The present invention is particularly concerned with the provision of a compound stabilizer and dust pan control of simplified construction for sweepers of the type described. As to the dust pan control features, the improved control provided is designed to not only selectively maintain the dust pans in open and closed positions but to also serve as a manual actuator for dumping the pans, certain parts of the control being accessibly located in external relation to the sweeper casing for this purpose.

In the exemplary sweeper illustrated dust pan controls constructed in accordance with the invention are duplicated at opposite ends of the sweeper. As shown, each control comprises a compound spring and handle member 37 having two spaced vertical legs 39 interconnected at their top ends by a horizontal handle 40, Figs. 1 and 4. As the pan controls 37 are integrated into the sweeper, the control legs 39 are suitably mounted on the inner faces of the end plates 24, each leg extending through individual upper and lower guides 42 and 43 on the end plates, Figs. 3 and 6. The lower ends of the legs 39 pivotally engage the respective dust pans 17, 18 at points on the pans which assume positions below the pivotal support pins 36 when the pans are in closed position, Fig. 6.

Preferably, the connection to the pans is effected by forming horizontal extensions 45 on the lower ends of the legs. Each extension 45 is engaged in a notch 46 in the lower edge of the contiguous dust pan support flange 34. The notches 46 are so shaped that the leg extensions 45 are at all times capable of transmitting outward horizontal forces and vertical forces to the pan support flanges 34. The construction also enables the lateral extensions 45 to transmit downward forces to the flanges when the pans are in the open position, Fig. 7.

Each control member 37 including the legs 39 preferably is fabricated from an integral bar or wire of spring steel or the like, the configuration of the member 37 being such that the legs 39 are placed under lateral stress upon assembly of the sweeper parts, causing the lower ends of the legs to exert horizontal pressure on the dust pans through the leg extensions 45. Normally, the extensions 45 engage the pans at points below the support pivots 36 and the legs 39 press outwardly on the pans to bias them toward closed position.

Referring more particularly to the handles 40 of the control members 37, it will be seen from Figs. 3, 4, and 5, that each handle forms a transverse hand grip element outwardly offset from the legs 39 and connected at opposite ends to the legs by horizontal extensions 47. As shown, the extensions 47 protrude through vertical slots 49, 50 in the end plates 24 and the end shells 28 to dispose the respective handles or grippers 40 in external relation to the sweeper casing 11.

Each handle 40 is spaced externally a sufficient distance from its associated end shell 28, Fig. 5, to enable the user conveniently to grasp the

handle. Preferably the handles are disposed in vertical indentations 51 formed in the end shells to extend downwardly from the top side of the casing 11, Figs. 1, 3, and 5. In this manner, the handles are spaced from the contiguous shell walls and are at the same time shielded by the surrounding portions of the shells to guard against marring of furniture.

The convenience afforded to the user by the novel dust pan control arrangement is evident from a résumé of its operation. All that is required for dumping the pans is that one or both of the handles 40 be shifted upwardly. This movement of the handles raises the control legs 39 which in turn swing both dust pans downwardly into dumping position, Fig. 7. If it is desired that pans be held open for any appreciable time, the handles 40 are moved upwardly sufficiently to raise the leg extensions 45 substantially to the level or above the pivots 36. The horizontal biasing forces of the legs 39 then act in lines above the pivots 36 to maintain the pans in open position.

If, on the other hand, there should be no reason to hold the pans 17, 18 in open position, the handles 40 are lifted sufficiently to dump the pans, but not enough to raise the leg extensions 45 to dead center position. The spring forces of the legs 39 on the pans thus continue to act in lines below the pivots 36 and are self-operative to close the pans immediately upon release of the handles 40. This self-closing feature of the pan control also facilitates closing of the pans even when the pans have been locked in open position by the control. In these instances all that is necessary to close the pans is that one of the handles be pushed downwardly a short distance to move the leg extensions 45 back through dead center position. At that time the self-closing action takes over, and the pans snap into closed position.

Thus it is clear that the novel dust pan control affords an extremely convenient and effective means for dumping the pans to empty the sweeper. The control handles 40 are readily accessible to the user and may be manipulated directly from a position above the top of the sweeper casing. The position of the handles outside the casing 11 keeps the handles free of dust so they do not soil the hands of the user when the sweeper is emptied.

In addition to affording convenient control of the dust pans 17, 18, the compound control members 37 cooperate with the sweeper bail 13 to improve the sweeping action of the sweeper and to maintain the sweeper handle 12 in raised position when the sweeper is not in use. As shown in Figs. 3 and 5, the handles of the members 37, which are somewhat resilient in character, are disposed in position to yieldably engage the two respective arms 52 of the bail 13 which are pivotally attached to the end shells 28 of the casing 11 just below the mid-portions of the handles. It will be noted that in exerting an outward pressure on the arms 52 the handles 40 react on the casing 11 through the links 47 which abuttingly engage the guides 42.

Each handle 40 is formed to have a generally W-shaped configuration, the central portion being indented inwardly to present an outwardly open notch 54 which receives the associated bail arm 52 when the bail 13 is raised into vertical position, Figs. 4 and 5. The retaining action of the notches is sufficient to maintain the bail 13 and handle 12 yieldably in vertical position once it

is raised to this position. Thus, when the operator is temporarily not using the sweeper, the handle 12 may be left in a standing position to eliminate any necessity for stooping to pick up the handle when the sweeper is to be used again.

The end sections 55 of the handles 40 on opposite sides of the central notches 54 engage the arms 52 whenever the handle 12 is pivoted to either side of its standing position in the course of moving the sweeper back and forth over a carpet. This engagement of the parts results in frictional resistance to pivotal movement of the handle 12 relative to the casing 11 incident to operation of the sweeper and thereby induces a stabilizing effect to the action of the handle 12 in controlling the sweeper. This stabilization improves the operation of the sweeper and is particularly advantageous in sweepers which are floatingly mounted on their floor wheels, such as the sweeper shown in my previously identified copending application.

It will be noted from the preferred construction illustrated that the extensions 55 are inclined toward the casing 11 from their inner to their outer ends. The shaping of the handles 40 to bring about this disposition of the extensions enables the arms 52 to slide back up on the handles in the event they are pivoted beyond either of the handle extremities. Moreover, the inclination of the extensions 55 induces longitudinal forces in the handles 40 which are cumulative with the frictional reaction of the arms 52 on the handles to bring about a most effective stabilizing action on the sweeper.

The simplicity of the construction provided by the invention is manifest from a review of the drawings. Each of the combined controls 37 is fabricated from a single length of spring bar stock, obviously a very inexpensive construction. Moreover, the controls can be easily assembled into the sweeper to be operatively connected with the dust pans 17, 18 through engagement with the flange notches 46.

As assembled into the sweeper, the controls 37 serve a number of different purposes of an advantageous nature. They afford convenient control of the dust pans 17, 18 and also serve to close the pans or selectively maintain them in either closed or open position. Furthermore, the novel controls cooperate with the sweeper bail 13 to maintain the bail in raised position and to impart an improved action to the sweeper itself.

I claim as my invention:

1. In a carpet sweeper of the class described, the combination of a generally rectangular casing, two opposed dust pans pivotally mounted in said casing, a handle bail having two spaced arms pivotally attached to opposite ends of said casing, a compound stabilizer and dust pan control member having spaced resilient legs pivotally connected to said respective pans, a control handle interconnected between said legs and positioned outside of said casing in engagement with one of said arms, said handle being formed to present an outwardly open medial notch adapted to coact with said one arm to maintain said bail in raised position, said handle having end sections on opposite sides of said notch adapted to engage said one arm for stabilizing said sweeper upon inclination of said bail from its raised position as an incident to operation of the sweeper.

2. In a carpet sweeper of the class described, the combination of a generally rectangular casing, two opposed dust pans pivotally mounted in said casing, a handle bail having two spaced arms

pivotally attached to opposite ends of said casing, a compound stabilizer and dust pan control member having spaced legs pivotally connected to said respective pans and slidably disposed in guides on said casing, a control handle interconnected between said legs and positioned outside of said casing in offset relation to the contiguous portion thereof, said handle being biased into engagement with one of said arms for stabilizing said sweeper during use, and the reaction of said arm on said handle being absorber by said guides.

3. In a carpet sweeper of the class described, the combination of a generally rectangular casing, two opposed dust pans pivotally mounted in said casing, a handle bail having two spaced arms pivotally attached to opposite ends of said casing, a compound stabilizer and dust pan control member having two spaced resilient legs pivotally connected to said respective pans, a control handle interconnected between said legs and positioned outside of said casing in offset relation to a contiguous portion of said casing and being adapted to raise and lower said legs for opening and closing said pans, said handle being biased into engagement with one of said arms, said handle having an outwardly open medial notch adapted to coact with said one arm to maintain said bail in raised position, and two inclined end sections on opposite sides of said notch adapted to engage said one arm for stabilizing said sweeper when said bail is inclined from its vertical position in the course of operation of the sweeper.

4. In a carpet sweeper of the class described, the combination comprising a casing including two spaced end plates defining an inner compartment, two end shells on opposite ends of said casing cooperating with said end plates to define two upwardly and laterally closed end compartments, two dust pans disposed in said inner compartment, each pivotally connected to said respective plates, one of said end shells forming a medial indentation in the upper portion thereof and defining a pair of vertical slots on opposite sides of said indentation, said end plate adjacent said one end shell having guides thereon aligned with said end shell slots, a compound stabilizer and a dust pan control member including two upright resilient legs slidably engaging said end plate guides and pivotally connected at their lower ends to said respective dust pans, extension members on said legs projecting through said end shell slots, and an elongated handle interconnected between the outer ends of said extension members and spanning said shell indentation, a sweeper handle bail including two spaced arms pivotally attached to said respective end shells at a level below said handle, and the medial portion of said handle being formed with an outwardly open medial notch for receiving the adjacent handle bail arm when the latter is in raised position, opposite ends of said handle being adapted to engage the adjacent bail arm when the arm is in inclined position to stabilize said casing.
